SWAGING TOOL FOR TUBES

Charles F. Tuttle, Richmond, Calif., assignor to
 Standard Oil Company of California, San
 Francisco, Calif., a corporation of Delaware

Application March 28, 1941, Serial No. 385,725

11 Claims. (Cl. 205—5)

This invention relates to apparatus for reducing the diameter of a metal tube and particularly to one which is adapted to be used in a restricted location and to be placed over the exposed end of a tube which has been enlarged for a short distance along its length by machining or rolling operations and whose diameter is to be reduced substantially to its original value.

In that part of the petroleum distillation art which utilizes tubular heaters or furnaces, and particularly in the case of certain types of alloy steel tubes, the ends of the tubes which are rolled or expanded into junction boxes or return headers become enlarged in diameter due to the severe cold working which they receive, and at the same time the tube seats in the headers themselves become correspondingly stretched. When it becomes necessary to remove the headers to replace tubes that are no longer serviceable, the normal ends of new tubes will be found to be too small in diameter to fit the seats of the previously used headers, and when replacing headers, the normal size tube seats are too small in diameter to receive tubes which have been enlarged by previous use. Also, when tube ends are shrunk so that they may be removed from the header to replace an adjacent tube, the tube end is often forced out-of-round.

Heretofore replacement headers have been specially reborred over-size to allow not only for the expansion of the tube end but also for the out-of-roundness, making it necessary to have a very loose fit between the tube and its seat in the header. Since the effects are cumulative, tubes that have been rolled into two or three headers or have been rerolled because of leaks are considerably expanded, frequently one-fourth inch or more oversize. The tube and walls are also undesirably thinned by both the increase in diameter and by the flow of metal set up during the rolling operations.

This invention is primarily but not exclusively applicable to the reconditioning of expanded or enlarged tube ends in place in a furnace. Usually a tube extends only a few inches through its supporting tube sheet and is closely surrounded by other tubes and their connecting headers. For this reason any tool which may be used for such reconditioning is required to be portable, compact and adapted to be used in confined locations and with a minimum of auxiliary power for its operation.

This invention comprehends broadly a die holder which is generally cylindrical and elongated and is adapted to be placed over the en-

larged end of the tube to be swaged. Within the holder is positioned a circular die, which may be a plurality of segments adapted to be expanded while the die holder is placed over the tube and 5 then contracted to surround the tube closely at a point removed from its outer end where the diameter of the tube is substantially normal. Means are provided to draw this assembly outwardly over the enlarged end of the tube, constricting it and causing the metal to flow back to its original dimensions.

It is an object of this invention to provide an improved swaging tool that will reduce the diameter of an enlarged tube end to its original size. Another object is to provide a device of this kind that is portable and may be operated by one or two men.

Another object is to provide a swaging tool that may be used on furnace tubes while they are in place without requiring removal from the furnace.

Another object is to provide a tube swaging tool in which a plurality of die segments are adapted to be moved axially of a die holder and 25 also radially therein to permit installation and operation with a minimum of external adjustments and parts.

These and other objects and advantages will be apparent from the following description and from the accompanying drawing which forms a part of this specification and illustrates a preferred embodiment of this invention.

In the drawing,

Figure 1 is a longitudinal and part sectional view of a device embodying this invention in place on a tube that is to be swaged to its normal diameter.

Figure 2 is a transverse sectional view on line II—II of Figure 1 showing the die segments and the adjusting sleeve therefor with the segments in their contracted position.

Figure 3 is a transverse sectional view on line III—III of Figure 1 showing the axial position of the anvil within the yoke frame of the device.

Figure 4 is an enlarged longitudinal sectional view illustrating the configuration and arrangement of the die segments.

Referring to the drawing, and particularly to Figure 1, reference numeral 10 illustrates a tube which is supported by means such as sheet 11 so that a few inches of the outer end of the tube project outwardly from the furnace or other structure in which the tube is mounted. To illustrate the confined nature of the space between tubes, a fragmentary view of a second tube 12

with a header 13 is shown immediately below tube 10. Other tubes and headers, not shown, may entirely surround the tube 10. Due to frequent removal and replacement of headers, or to other causes, the outer end of tube 10 has been enlarged as indicated at 14 so that its outside diameter is no longer the same as the normal diameter of tube 10.

The tube end reducing apparatus of this example consists essentially of a cylindrical, elongated die holder 15 provided with a bore 16 throughout the greater portion of its length. At the outer end of bore 16 is an inwardly tapered shoulder 17 against which the die segments 18 are adapted to seat when they are in their contracted position. Desirably, die segments 18 are of the form shown in Figure 4, having an outer tapered face 19, which is adapted to seat on and be supported by the inwardly tapered shoulder 17 of die holder 15, and a generally cylindrical portion 20. The cylindrical portion 20 of each segment is desirably recessed radially as at 21 to form notches which cooperate with corresponding notches in adjacent segments to provide recesses 22 for a purpose which will be explained below. The inner faces 23 of segments 18 are desirably tapered as illustrated in Figure 4 and form the actual contact faces which engage with the enlarged portion 14 of tube 10 to draw the latter down to its normal diameter. For convenience in holding the segments in their assembled position and to insure that they will expand uniformly outwardly when they are drawn into bore 16 of die holder 15, an annular recess 24 may be provided within the segment assembly for the reception of a circular spring 25 (Figure 1).

In order to move the die segment assembly axially within bore 16 of die holder 15 and to insure that it will contact the inwardly tapered shoulder 17 throughout the circumference of the segments, an adjusting sleeve 26 is provided within holder 15 and is fitted at its outer end with a plurality of radial keys 27 that engage notches 22 of the die segment assembly. This will permit radial inward and outward motion of the segments as they are expanded into bore 16 or contracted against shoulder 17.

The inner end of die holder 15 is preferably connected by means such as a threaded joint 28 to an axial yoke 29, a part of which may be cylindrical as at 30 and the remainder of which may consist of opposed flat bars or members 31 connected at their outer ends by a cross-member 32. At the junction of bars 31 with cylinder 30 of yoke 29 there is positioned a flange 33 which may be adjustably secured to the end face of cylinder 30 by means of studs 34 and nuts 35. Adjusting sleeve 26 desirably extends substantially throughout cylindrical portion 30 of yoke 29 and is centered by means of a guide bushing 36, against the outer face of which flange 33 is adapted to be secured by means of studs 34 and nuts 35.

In order to force die segments 18 and die holder 15 outwardly over the enlarged end 14 of tube 10, expansible means are provided within yoke 29 that will engage the outer end face of tube 10 and the cross-member 32 of yoke 29 to force them apart. In this embodiment and for convenience of operation these means consist essentially of an anvil 37 provided with an enlarged head 38 that contacts the end face of tube 10 and is slightly smaller than the normal diameter of tube 10 so that it may pass through die segments 18

when they are in their contracted position. The opposite face of anvil 37 may be recessed as at 39 to receive spacer members 40 and 41 which are guided by the bores of flange 33 and guide bushing 36 to maintain the anvil in a truly axial position with respect to yoke 29 and tube 10. An auxiliary guide flange 42 may be provided within adjusting sleeve 26. In addition to these guides, a ring 43 for spacer 41 may be positioned between and supported by the flat bar members 31.

In this example the motive power or expansible means for forcing anvil 37 against the end face of tube 10 consists of a conventional hydraulic jack 44 which is adapted to seat on cross-member 32 of yoke 29 and to have its ram element 45 received in recess 46 of spacer 41.

In operation, adjusting sleeve 26 is withdrawn slightly from die holder 15 so that die segments 18 will be in their expanded and circumferentially separated position within bore 16 of the holder. The expanded die thus formed and the outer end of the holder are then placed over the enlarged portion 14 of tube 10 so that they surround the normal or undistorted portion of that tube. Adjusting sleeve 26 is then forced into die holder 15 so that the die segments 18 are seated on the inwardly tapered shoulder 17, the radial notches 22 and keys 27 permitting this inward and circumferential contraction of the die segments. Flange 33 and guide bushing 36 are seated against sleeve 26 and are secured by means of nuts 35 on studs 34.

After the anvil spacers 40 and 41 are inserted, the hydraulic jack 44, or whatever expansible means are used for this purpose, is inserted in yoke 29 and is actuated to force the enlarged head 38 of anvil 37 against the end face of tube 10 expelling the latter from the constricted bore formed by the die segments 18 within holder 15 and contracting the tube to a predetermined or desirably its normal diameter. It is desirable to place a lubricant such as graphite and oil upon the inner face of die segments 18 and on the outer surface of the enlarged end 14 of tube 10 which will prevent undue friction and abrasion of these parts. Also, if the tube is greatly enlarged it may be necessary to provide die segments of different radial thickness so that several passes of the die over the enlarged end may be made. With the construction shown, however, it is possible to make the reduction in a series of steps, by suitable adjustment of sleeve 26 to advance the segments 18 progressively into holder 15 and against the tapered shoulder 17.

In conclusion, it will be appreciated that a new and improved form of tool for this purpose has been provided in the example described and illustrated. Obviously numerous changes could be made without departing from the invention and all such changes that come within the scope of the appended claims are embraced thereby.

I claim:

1. Means for reducing the diameter of an enlarged end of a ductile metallic tube, such as an oil heater tube projecting outwardly from a furnace, comprising an elongated die holder adapted to be placed over the enlarged tube from its outer end, a plurality of die segments in said holder and selectively adapted to be expanded to pass over the enlarged portion of said tube and to be contracted to the normal diameter of said tube beyond the enlarged portion thereof, and means engageable with the end face of said tube to exert a force thereagainst for drawing said die holder with said die segments in their contracted

position toward the end of said tube to contract the enlarged portion thereof.

2. Means for reducing the diameter of an enlarged end of a ductile metallic tube, such as an oil heater tube projecting outwardly from a furnace, comprising a circumferential die holder adapted to be placed over the enlarged tube from its outer end, a plurality of die segments adapted to be positioned within said die holder in an expanded position, an inwardly tapered shoulder in said die holder near the outer end thereof, means for positioning said segments in a contracted position against said tapered shoulder and closely surrounding said tube beyond the enlarged portion of the latter, and means for drawing said die holder and said contracted die segments toward the end of said tube to reduce the enlarged portion thereof to a predetermined diameter.

3. Means for reducing the diameter of an enlarged tube end according to claim 2, with the addition of a yoke extending axially from said die holder, and in which said die holder drawing means are extensible and are adapted to be positioned between said yoke and the outer end face of said tube.

4. Means for reducing the diameter of an enlarged end of a ductile metallic tube, such as an oil heater tube projecting outwardly from a furnace, comprising a circumferential die holder adapted to be placed over the enlarged tube from its outer end, a plurality of die segments in said holder and selectively adapted to be expanded to pass over the enlarged portion of said tube and to be contracted substantially to the normal diameter of said tube, and a yoke extending axially from said holder, said yoke adapted to receive an expandable means that will engage the outer end face of said tube to force said die holder and said segments toward the enlarged end of said tube to contract the same.

5. Means for reducing the diameter of an enlarged tube end according to claim 4, with the addition of axially movable means in said yoke, one end of said means adapted to engage the outer end face of said tube and the other end adapted to receive said expandable means to be moved thereby, and guide means in said yoke for said axially movable means.

6. Means for reducing the diameter of an enlarged tube end according to claim 4, with the addition of an axially movable anvil in said yoke, one end of said anvil adapted to engage the outer end face of said tube and the other end adapted to receive said expandable means to be moved thereby, and separately adjustable means in said yoke and outside of said anvil to position said die segments in expanded and contracted position.

7. Means for reducing the diameter of an enlarged end of a ductile metallic tube, such as an oil heater tube projecting outwardly from a furnace, comprising a generally cylindrical die holder adapted to be placed over the enlarged tube from its outer end, a plurality of die segments adapted to be positioned within said die holder in an expanded position, an inwardly tapered shoulder in said die holder near the outer end thereof, a sleeve in said die holder, radial slots and keys connecting said sleeve to said segments to permit radial motion of said segments, said sleeve being movable axially of said holder to position said segments in a contracted position against said tapered shoulder and closely surrounding said tube beyond the enlarged portion of the latter, and means for urging said die holder and said contracted segments toward the end of said tube to reduce the enlarged portion thereof to a predetermined diameter.

8. Means for reducing the diameter of an enlarged tube end according to claim 7 with the addition of a yoke extending axially from said die holder, and in which said die holder urging means engage said yoke and the end face of said tube, respectively, for the purpose described.

9. Means for reducing the diameter of an enlarged end of a ductile metal tube, such as an oil heater tube projecting outwardly from a furnace, comprising a die holder adapted to be placed over the enlarged tube from its outer end, means forming an expandable and contractible circular die at the outer end of said holder, means forming a yoke extending axially from said holder to receive an expandable means, such as a jack, and an axially aligned anvil in said yoke adapted to engage the end face of said tube and to be forced against said face by said expandable means to force the enlarged end of said tube into and through said die to reduce the diameter of said tube end.

10. Means for reducing the diameter of an enlarged tube end according to claim 9 with the addition of separate means in said die holder for selectively positioning said die in expanded and contracted position.

11. Means for reducing the diameter of an enlarged end of a ductile metallic tube, such as an oil heater tube projecting outwardly from a furnace, comprising a die holder adapted to be placed over the end of said tube, a segmental die in said holder having a bore smaller than the outer diameter of the enlarged portion of said tube, and means engageable with the outer end face of said tube to force said holder and die outwardly along said tube to contract the enlarged portion thereof.

CHARLES F. TUTTLE.
